UNITED STATES PATENT OFFICE.

CLYDE W. MUMMERY, OF DETROIT, MICHIGAN.

LIQUID-FUEL BURNER.

Application filed May 16, 1925. Serial No. 30,695.

This invention relates to liquid fuel burners and has for its principal objects to provide a plurality of contacts between the flame and the vessel to be heated to prevent rippling of the flame, to increase the speed with which the burner may be put in efficient operation, and to maintain proper relationship between the tubes of the burner.

Further objects and advantages of the invention will become apparent as the description is read in connection with the accompanying drawing, in which—

Fig. 1 is a sectional view through the preferred form of burner together with a fragment of the stove and the feed pipes;

Fig. 2 is a plan view of the same;

Figs. 3 and 4 are sectional views taken on the lines 3—3 and 4—4 of Fig. 1;

Fig. 5 is an elevation of the preferred form of burner with the feed pipe in section on the line 5—5 of Fig. 1; and

Fig. 6 is a sectional view of an alternative form of burner.

The reference numerals 10 and 11 indicate the outer and inner combustion tubes respectively which are concentrically arranged and define between them a vapor space 12. At their lower ends the tubes 10 and 11 are secured to a vaporizer 13 having therein a trough 14 for the fuel to be vaporized. The bottom of the outer vapor tube is received within an annular recess 15 in the vaporizer outside of the trough 14. The bottom of the inner combustion tube telescopes with a cylindrical portion 16 inside of the trough and adjacent to the top thereof. The tubes 10 and 11 are provided with the usual perforations 17 and 18 by which air is supplied to the vapor as it rises through the vapor space.

A cylindrical air drum 19 surrounds the outer combustion tube and is equipped at its upper end with an air drum cap 20 for diverting air inwardly adjacent to the upper end of the combustion tubes. In the form shown the air drum cap is a casting having a cylindrical base 21 telescoping with the upper end of the air drum and a somewhat spherical flange 22 arching towards the discharge end of the vapor space. Four lugs 23 depend from the cylindrical base 21 along the outside of the air drum. These lugs are provided with threaded perforations at 24 to receive screws 25 which pass through the air drum, the outer combustion tube and have ball points 26 resting against

the outer wall of the inner combustion tube. These screws, therefore, not only secure the air drum cap to the air drum, but support the air drum on the outer combustion tube 60 and maintain the proper spacing between the air drum and the outer combustion tube and between the two combustion tubes.

A flame control ring 27 is supported above the annular vapor space 12, preferably from the air drum cap 20. In the present illustration this ring is cast and has a plurality of radial arms 28 terminating in depending legs 29, the lower reduced ends 30 of which are received in appropriate perforations in 70 the flange 22 of the air drum cap.

The vaporizer has a cylindrical bore 31 formed in a ring 32 supported from the trough or main body of the vaporizer by the stays 33. An air shaft 34 has its lower end seated in the bore 31 and extends upwardly concentric with and in spaced relation to the inner combustion tube. This air shaft is preferably imperforate except for relief vents 35 that may be located adjacent to its 80 upper end.

An air cap 36 closes the inner combustion tube and has a flange 37 closing the space between the inner combustion tube and the air shaft. Above this flange is a cylindrical portion 38 telescoping with the inner combustion tube and having an external shoulder 39 to rest on the top of that tube. Above the cylindrical portion the cap arches inwardly, as indicated at 40, and joins a substantially cylindrical core section 41, which extends to or above the bottom of the flame control ring 27. The arched portion of the air cap is provided with an annular series of perforations 42 for feeding air into the flame and vapor adjacent to the discharge end of the vapor space and below the flame control ring.

In operation the vaporized fuel rising from the trough 14 through the vapor space 100 is intermixed with air passing inwardly through the perforations 17 and 18 in the combustion tubes. As the flame and vapor passes out of this space, it is directed inwardly by the air drum cap and receives an annular series of jets of air through the perforations 42. These jets not only supply air to carry on the combustion, but draw the column of flame or a portion of it, 105 through the flame control ring, substantially as indicated by the arrow 43.

When a vessel is placed upon the grate 44

the flame divides at the flame control ring, part of it taking the course indicated by the arrow 45, with the result that there are two columns of flame passing from the burner 5 and impinging against the base of the vessel or other article to be heated. This effects a better mixture of the vapors and air and a more efficient transfer of heat from the flame to the vessel than that which 10 takes place in the burners of the prior art which deliver a single column of flame.

The action of the burner is enhanced by slightly flaring the upper end of the outer combustion tube, as indicated at 46 and 15 providing the flared portion with a series of perforations 47 by which the air rising in the space 48 between the air drum and the outer combustion tube is fed into the heated vapors just as they escape from the 20 vapor space.

The core 41 of the air cap prevents the flame from drawing into a narrow pencil at the point and forces it to maintain the annular form.

25 Air in the space 49 between the air shaft and the inner combustion tube must be relieved adjacent to the top or the flame will ripple. Relief may be effected by perforations 35 in the air shaft or perforations 50 30 (Fig. 2) in the flange 37 of the air cap. The exact size and number of these perforations will depend somewhat upon the particular size of burner and other conditions. The amount of relief required may be determined by a little experiment. Too little relief will manifest itself in a rippling flame; too great relief will manifest itself in an under supply of air through the perforations 18 of the inner combustion tube, which 40 will result in an odor.

The size, shape and arrangement of the perforations 42 also depends upon particular conditions. The object is to furnish the air in a plurality of jets at or near the point 45 where the flame is diverted inwardly by the air drum cap. If the air is supplied in an annular column, it does not mix well with the vapor and the flame; but by breaking up the column into a plurality of jets, the admixture is augmented and the resultant combustion improved. With a three and three-quarter inch ($3\frac{3}{4}$ '') inner combustion tube and a four and three-quarter inch ($4\frac{3}{4}$ '') outer combustion tube, sixteen (16) 50 perforations three-sixteenths ($\frac{3}{16}$ '') of an inch in diameter, with their centers on a three inch circle, gives the best results.

The size of the flame control ring 27 and its relation to the perforations 42 and the 55 air drum cap also depends somewhat on conditions. By raising and lowering the flame control ring, or changing its diameter and shape, the division of the flame may be varied. With the dimensions just mentioned 60 a ring with two and seven-eighths inch

($2\frac{7}{8}$ '') internal diameter and four inch (4'') external diameter supported one-half inch ($\frac{1}{2}$ '') above the perforations 42 gives the best results.

When the air cap is made of sheet metal 70 its walls are thinner than the usual casting and the jets escaping from the perforations 42 act somewhat differently. In such a construction the inner diameter of the flame control ring should be larger relative to the 75 circle of jets than when an air cap of cast iron is used. I have found that when the outer edges of the perforations 42 are about even with the inner edge of the flame control ring the operation is most satisfactory. 80

The external diameter of the flame control ring should never exceed the diameter of the outer combustion tube. If the internal diameter of the flame control ring is less than the distance between the outside 85 of the opposite perforations 42 the operation will be improved by chamfering the inner circle of the ring as indicated at 53.

In order to facilitate the assembly of the inner combustion tube with the vaporizer 90 the stays 33 are provided with upwardly extending guides 51 (Fig. 1) having curved upper edges 52 that will readily enter the lower end of the inner combustion tube as it is forced down to its seat in the vaporizer.

In the construction shown the air cap is made by casting to eliminate the expense of dies required to make it in either one or two pieces of sheet metal. An alternative construction is shown in Fig. 6 where the flange 37 is omitted and the upper end 133 of the air shaft is flared to close the upper end of the annular space 149, except for the relief vents 135. A variety of other 105 modifications will occur to those skilled in the art.

The vaporizer 13 is preferably made of aluminum and the mass is reduced to the minimum possible to correspondingly reduce the quantity of British thermal units required to raise the temperature of the vaporizer to the point necessary to properly 110 vaporize the low grade fuel.

In starting, the priming charge of gasoline, or other highly volatile fuel is inserted in the trough 14 and ignited. The combustion of this fuel serves to raise the temperature of the burner sufficiently to enable it to 115 vaporize the low grade fuels, such as kerosene. With the improved construction, immediately after lighting the priming fuel the low grade fuel may be turned on and the burner put into use.

At the base of the vaporizer are two depending flanges 76 and 77, each of which is provided with three perforations 78, to adapt the burner for use in either right hand oven stoves, or left hand oven stoves, or 120 stoves having no oven. 125

I claim as my invention:—

1. In a liquid fuel burner, the combination of a vaporizer, inner and outer combustion tubes defining an annular space above the vaporizer, an air shaft within and spaced from the inner combustion tube, an air cap closing the air shaft and the space between the air shaft and the inner combustion tube, said air cap having a plurality of perforations therein, an air drum surrounding the outer combustion tube, and a flame control ring above the upper ends of the combustion tubes. 5
2. In a liquid fuel burner, the combination of inner and outer combustion tubes spaced apart and provided with perforations, a vaporizer closing the space between the said tubes at the bottom and having a fuel trough communicating with said space, a flame control ring above said combustion tubes, an air drum surrounding the outer combustion tube and having means to direct air inwardly adjacent to its upper end, an air shaft within the inner combustion tube, 15 and means cooperating with the air shaft to draw the flame inward adjacent to the upper end of the inner combustion tube. 20
3. In a liquid fuel burner, the combination of inner and outer combustion tubes defining an annular vapor space and having perforations communicating with said space, a vaporizer closing said space at the bottom and having a fuel trough communicating therewith, a flame control ring of less outside diameter than said annular space and supported above its upper end, an air drum surrounding the outer combustion tube having means at its upper end for directing the air inwardly, an air shaft within the inner 25 combustion ring, an air cap obstructing the flow of air directly upward from said shaft and supplying air to the flame adjacent to the flame control ring. 30
4. In a kerosene oil burner, the combination of inner and outer combustion tubes defining an annular vapor space and having perforations communicating with said space, a vaporizer closing said space at the bottom and having a fuel trough communicating therewith, an air drum surrounding the outer combustion tube having means at its upper end for directing air inward, said outer combustion tube having a slight perforated flare extending only a short distance 35 downwardly from its top edge. 40
5. In a liquid fuel burner, the combination of inner and outer combustion tubes defining an annular vapor space and having perforations communicating with said space, a vaporizer closing said space at the bottom and having a fuel trough communicating therewith, a flame control ring of less outside diameter than said space and supported above its upper end, an air drum surrounding the outer combustion tube hav- 45
- ing means at its upper end for directing the air inward, an air shaft within the inner combustion ring, and an air cap closing the inner combustion tube and air shaft and having an annular series of outlets adjacent to the flame control ring. 50
6. In a liquid fuel burner, the combination of inner and outer combustion tubes defining an annular vapor space, and having perforations communicating therewith, a vaporizer communicating with the vapor space at the bottom thereof, an air shaft within the inner combustion tube, an air cap closing the inner combustion tube and the space between said inner combustion tube and the air shaft, said cap having an annular series of perforations to feed air to the flame above said annular space, means for feeding an excess of air to the lower portion of the space between the inner combustion tube and the air shaft and means for relieving air in the space between the inner combustion tube and the air shaft adjacent to the upper end thereof. 55
7. In a liquid fuel burner, the combination of inner and outer combustion tubes defining an annular vapor space and having perforations communicating therewith, an air drum surrounding the outer combustion tube and having means at its upper end for directing air inwardly, a flame control ring above the annular space, means for supporting said ring on the air drum, an air shaft within the inner combustion tube, and means for limiting the flow of air through the air shaft and the inner combustion tube and feeding air in an annular series of jets to the flame adjacent to the upper end of said annular space. 60
8. In a liquid fuel burner, the combination of inner and outer combustion tubes, an air drum surrounding the outer combustion tube, and a series of screws in angular relation to each other and engaging the air drum and the two combustion tubes to hold them in proper spaced relation. 65
9. In a liquid fuel burner, the combination of inner and outer combustion tubes, an air drum surrounding the outer combustion tube, an air drum cap on said air drum having threaded perforations, a series of screws in angular relation to each other and engaging the air drum and the inner and outer combustion tubes. 70
10. In a liquid fuel burner, the combination of inner and outer combustion tubes defining an annular vapor space and having perforations communicating therewith, a vaporizer communicating with the vapor space at the bottom thereof, an air shaft within the inner combustion tube, an air cap closing the inner combustion tube and the space between said inner combustion tube and the air shaft, said air cap having an annular series of perforations to feed air to the flame above said 75
- 80
- 85
- 90
- 95
- 100
- 105
- 110
- 115
- 120

- 130

annular vapor space, the space between the air shaft and the inner combustion tube being open at the bottom sufficient to admit an ample supply of air along the inner wall of the inner combustion tube throughout its length and means for relieving air in the space between the inner combustion tube and the air shaft adjacent to the upper end thereof.

10 11. In a liquid fuel burner, the combination of inner and outer combustion tubes, an air drum surrounding the outer combustion tube and screws in angular relation passing through the air drum and the outer combustion tube and bearing against the inner combustion tube.

12. In a liquid fuel burner, the combination of a trough shaped vaporizer of thin aluminum, inner and outer combustion tubes defining an annular space above the vaporizer and having perforations communicating with that space, an air shaft within and spaced from the inner combustion tube, an air cap closing the air shaft and the space between the air shaft and the inner combustion tube, said air cap having a plurality of

perforations therein, an air drum surrounding the outer combustion tube and a flame control ring above the upper ends of the combustion tubes.

13. In a liquid fuel burner, the combination of inner and outer combustion tubes defining an annular vapor space and having perforations communicating therewith, a trough shaped vaporizer of thin aluminum communicating with the vapor space at the bottom thereof, an air shaft within the inner combustion tube, an air cap closing the inner combustion tube and the space between said inner combustion tube and the air shaft, said cap having an annular series of perforations to feed air to the flame above said annular space, means for feeding an excess of air to the lower portion of the annular space between the inner combustion tube and the air shaft and means for relieving air in the space between the inner combustion tube and the air shaft adjacent to the upper end thereof.

In testimony whereof I affix my signature.

CLYDE W. MUMMERY.
